(57) **CLAIM**

I claim the ornamental design for a tent having integral inflatable supporting ribs, as shown and described.

DESCRIPTION

FIG. 1 is a perspective view of a tent having integral inflatable supporting ribs showing my new design showing an entry flap partially opened, all other views showing the entry flap closed;

FIG. 2 is a front elevational view thereof;

FIG. 3 is a rear elevational view thereof;

FIG. 4 is a left side elevational view thereof, the right side elevational view being a mirror image thereof;

FIG. 5 is a top plan view thereof; and,

FIG. 6 is a bottom plan view thereof.
